WIDE-BEAM FLOODLIGHT

Dallas L. Calmes, Bellaire, Tex.

Application March 22, 1955, Serial No. 35,151

Term of patent 14 years

(Cl. D48—20)

Fig. 1

Fig. 2

Fig. 3

Fig. 4

Fig. 1 is a front perspective view of a wide-beam floodlight showing my new design;

Fig. 2 is an end elevational view thereof looking at the right of Fig. 1;

Fig. 3 is a front elevational view; and

Fig. 4 is a top plan view.

I claim:

The ornamental design for a wide-beam floodlight, as shown.
